[57] CLAIM

The ornamental design for a combined light and speaker

housing for an emergency vehicle, substantially as shown and described.

DESCRIPTION

FIG. 1 is a perspective view of a combined light and speaker housing for an emergency vehicle embodying my new design, showing the front, top, and one side of the housing;

FIG. 2 is a perspective view of the housing shown in FIG. 1 on a reduced scale showing the rear, top, and other side thereof;

FIG. 3 is a top plan view of the package shown in FIG. 1;

FIG. 4 is a front elevational view of the housing shown in FIG. 1;

FIG. 5 is a side elevational view of the housing shown in FIG. 1;

FIG. 6 is a bottom plan view of the housing shown in FIG. 1;

FIG. 7 is a perspective view of a second embodiment of a combined light and speaker housing for an emergency vehicle embodying my new design, showing the front, top, and one side of the housing;

FIG. 8 is a perspective view of the housing shown in FIG. 7 on a reduced scale showing the rear, top, and other side thereof;

FIG. 9 is a top plan view of the housing shown in FIG. 7;

FIG. 10 is a front elevational view of the housing shown in FIG. 7;

FIG. 11 is a side elevational view of the housing shown in FIG. 7; and

FIG. 12 is a bottom plan view of the housing shown in FIG. 7.
